UNITED STATES PATENT OFFICE.

PETER MERFELD, OF MARBLE ROCK, IOWA.

FOLDING STOOL.

1,281,189.

Specification of Letters Patent.

Patented Oct. 8, 1918.

Application filed February 16, 1918. Serial No. 217,561.

To all whom it may concern:

Be it known that I, PETER MERFELD, a citizen of the United States, residing at Marble Rock, in the county of Floyd and State of Iowa, have invented certain new and useful Improvements in Folding Stools, of which the following is a specification.

This invention relates to folding stools which are particularly adapted for use as an auxiliary step to assist passengers in alighting from trains.

The object of the invention is to provide a stool of this character which while strong and capable of withstanding severe strains, is yet operable by one hand for collapsing and setting up.

Another object is to provide a stool of this character having a hand grip at the center, which when grasped, and the stool lifted, will cause the folding of the stool and provide means for suspending it from a nail or other suitable support.

Another object is to provide a folding stool which opens up into operative position by simply setting it down on a supporting surface, and which, when so set up will not collapse until lifted.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents an end elevation of a stool constructed in accordance with this invention in set-up operative position,

Fig. 2 represents a similar view in collapsed inoperative position,

Fig. 3 is a top plan view of a portion of the stool shown in open operative position,

Fig. 4 is a side elevation thereof.

In the embodiment illustrated, two pairs of legs 1 and 2 are mounted for pivotal movement on a horizontal metal rod 3 at the opposite ends thereof. Each pair of legs is exactly alike and they are preferably constructed of metal, but obviously they need not necessarily be made of this material.

As shown, each of the legs has its inner or upper end curved laterally inward as shown

in Figs. 1 and 2, and these ends are pivotally connected with rods 4 and 5, which rods also extend through bearings 6 formed in the outer ends of sectional cross bars as 7, it being understood that one of these bars 7 is disposed at each end of the stool. Clamping nuts 8 and 9 are also mounted on the rods 4 and 5, one being disposed adjacent the inner face of one of the legs and the other outside the bearing 6 as is shown clearly in Fig. 4.

The cross bars 7 are each composed of two sections 10 and 11, the inner ends of which are here shown made wider than their outer ends which carry the bearings 6, and are provided with lapping apertured ears 12 which are designed to receive a longitudinally extending connecting rod 13, the ends 14 of the sections being positioned in abutting relation when the stool is set up into operative position as shown in Fig. 1.

The rod 13 is secured in operative engagement with these overlapping apertured ears of the sectional bars by means of clamping nuts 15 and intermediately its ends it has an upstruck or offset substantially U-shaped portion 16 to form a hand grip for the stool as is shown clearly in Figs. 2 and 3. This hand grip is designed to extend between two top or platform sections 17 and 18 which are formed of any suitable material preferably of hard wood sufficiently thick to resist the strains to which the stool of this character would be subjected. These boards or platform sections 17 and 18 may be of any suitable or desired width, according to the width of the stool and are secured to the cross bar sections 10 and 11 by riveting or in any suitable manner. These boards are shown bound around their outer edges by metal strips 19 composed of aluminum or other suitable wear resisting material which not only impart a finish to the stool but prevent wearing of the wood around the edges.

The inner meeting edges of the boards 17 and 18 are recessed midway their ends as shown at 20 to provide a space for the passage of the hand grip 16 so as to afford ample space for the passage of the fingers of the user through said grip.

The legs of each pair 1 and 2 are recessed on their meeting faces and provided with shoulders 21 and 22 so that the edges of the legs of each pair may abut against said shoulders as shown in Fig. 1 for pre-

venting undue spreading of the legs, and which assist in supporting the weights to be borne by the stool.

Longitudinally disposed connecting rods 5 unite the pairs of legs at points beyond their pivotal connection as is shown clearly in Figs. 1 and 4, these rods operating to brace the legs and prevent their spreading longitudinally. The free ends of these legs 10 may be finished in any suitable or desired manner, being here shown provided with rounded feet 24 formed by bending the ends of the legs inwardly into the loops shown in Figs. 1 and 2, and which facilitate the opening of the stool when it is deposited on the ground or other supporting surface.

In the use of this improved stool, when it is 15 in setup operative position as shown in Fig. 1 with the hand grip 16 disposed in the recesses 20 of the platform sections 17 and 18, said grip being positioned below the top faces of said boards so as not to interfere with the stepping of passengers thereon or to cause tripping of said passengers, when it is 20 desired to collapse the stool, the trainman or other person grasps the handle 16 and lifts the stool. When so lifted, the members of the hinged platform, will drop into parallel relation as shown in Fig. 2 and the connecting pairs of legs 1 and 2 will also fall into alignment with these platform sections in the position shown in Fig. 2 and the stool 25 may then be suspended from a nail or other suitable support by means of the grip 16 which performs the double function of a support and of a hand grip for lifting the stool.

When it is desired to set the stool up for use, all that is necessary is to take hold of the grip 16, disengage it from its support,

and set the stool down on the supporting surface, when the legs will immediately spread into the position shown in Fig. 1, carrying with them the platform sections 17 and 18 so that they will be arranged in flush horizontally aligned relation to form the top of the support and the device is then ready for use either to operate as an auxiliary step for use by train men or as a stool for any other purpose.

From the foregoing description, taken in connection with the accompanying drawings, the advantages of the construction and of the method of operation will be readily apparent to those skilled in the art to which the invention appertains and while I have 55 described the principle of operation of the invention together with the device which I now consider to be the best embodiment thereof, I desire to have it understood that the device shown is merely illustrative and 60 that such changes may be made as are within the scope of the claimed invention.

I claim:

A folding stool composed of sections, a pintle hingedly connecting said sections 65 along one side edge, a hand grip carried by said pintle for lifting and lowering the stool, stops for limiting the opening movement of said sections, and legs pivoted to the free edges of said sections, the grasping of said 70 grip and the lifting of the stool operating to collapse the stool.

In testimony whereof I affix my signature in presence of two witnesses.

PETER MERFELD.
